(57) **CLAIM**

The ornamental design for a device for prevention or treatment
of cervical cancer, as shown and described.

DESCRIPTION

The present application is also related to U.S. application
Ser. No. 29/739,544 and U.S. Pat. No. 9,738,528.

FIG. 1 is a front view of the device for prevention or treatment
of cervical cancer showing my design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The solid lines shown and described in the drawings form
the claimed design. The broken lines are for environmental
purposes only and form no part of the claimed design. The
design shown and described is not to be limited to any
particular size and may be scaled larger or smaller.
